TEXTILE APPARATUS

Richard Henry Baines, Thomas Eccles, and Stephen Miller Fulton, Spondon, near Derby, England, assignors to Celanese Corporation of America, a corporation of Delaware

Application March 8, 1947, Serial No. 733,368
In Great Britain March 12, 1946

5 Claims. (Cl. 28—54)

1

This invention relates to textile apparatus and particularly to leasing combs.

In leasing combs of the type hitherto commonly employed the dent wires are self-supporting, being bent to form support points in various ways. The present invention is concerned with new types of combs in which the dent wires are supported in the required positions by means of suitable members attached to or forming part of the frame of the comb.

According to the present invention, a leasing comb comprises a bottom baulk or bottom frame member, a series of long and short dents secured to said bottom baulk or bottom frame member and alternating along the length thereof, the spaces for the accommodation of warp threads between each short dent and the two adjacent dents being of different depths, and a top baulk or top frame member adapted to secure the tops of the long dents and detachable from the dents to allow warp threads to be dropped between the dents. A suitable form of top baulk for the purpose comprises a helical coil of wire, the successive turns of which are adapted to fit between the successive long dents, and two longitudinal members or strips adapted to fit inside said coil, one on each side of the series of long dents so as to lock the coil in position. The turns of the coil are slipped between the dents from one side of the comb, and one of the longitudinal members is slid endwise into the coil on the other side of the comb so as to effect the locking. The second longitudinal member may also be slid endwise into the coil, on the first-mentioned side of the comb, each time the top baulk is secured. Alternatively however, the second member, after the top baulk is once assembled, may be permanently fixed to the coil by the soldering of each turn of the coil thereto.

The bottom baulk may similarly comprise a wire coil for spacing the dents and a pair of longitudinal members fitting in said coil and, since the bottom baulk is not required to be removable, the turns of the coil may in this case be soldered to both longitudinal members, and to the dents also, to increase the rigidity of the comb. Rigid end members may be provided, secured to each end of the bottom baulk and extending parallel to the dents, and the longitudinal members of the top baulk may be detachably fixed to said end members.

Preferably the working position of the top baulk is slightly below the tops of the dents, so that the threads may be dropped in between the tips of the dents while they are still rigidly

2

held in position. The longitudinal member or members are then withdrawn, the spring is drawn out sideways from the dents and the threads drop down between the dents, after which the spring is reinserted between the dents and the longitudinal member or members replaced and fixed to the comb frame. In order to protect the tops of the dents and to help to keep them in alignment, there may be provided a metal cap which fits closely over the tops of the dents and is secured at each end to the end members.

By way of example one form of leasing comb according to the present invention will now be described in greater detail with reference to the accompanying drawings in which

Figure 1 is a front elevation of the comb and Figure 2 is a sectional side elevation.

The comb shown in the drawings comprises two D-shaped members 3 cut out of metal plate having a thickness equal to the width of the dents, as indicated by the section 4 shown in the right-hand part of Figure 1. The curved portions 5 of the D-shaped members serve as handles and the straight portions 6 constitute vertical members to which the baulks and other horizontal portions of the comb are attached.

The bottom baulk of the comb comprises two narrow strips 7 fixed at each end to either side of the bottom of the straight portion 6 of the handles. The lower ends of the dents 8 fit into the spaces between the strips 7. The bottom baulk also comprises two members 10, each of which is in cross-section a segment of a circle and which are fixed to the handles 3 at points just above the strips 7. Around the members 10 is wound a length of steel wire 11 in the form of a spiral, which is fixed to the bottom baulk by soldering as indicated at 12 (Fig. 2). The dents 8, 9, which are alternately long with straight ends (dents 8), and short with slightly bent ends (dents 9) are spaced along the length of the comb by the coils of the spiral wire 11 and are aligned transversely by means of the baulk members 7.

Each short dent 9 is soldered to an adjacent long dent 8 on one side thereof at a point 13 approximately $\frac{1}{4}$ inch below the tip of the short dent so that the space between dents on that side of the short dent is shallower than the space between dents on the other side and constitutes a hook into which a warp thread can be located. This also serves to increase the rigidity of the assembly.

The upper baulk also comprises two members 15, 16 of segmental cross-section which are de-

tachably located on the straight portions 6 of the handles 3 by means of bolts 17 and wing-nuts 18 and which pass through and support a spiral spring 19. For ease of withdrawal the member 15 is slightly longer than the other member 16, both members, 15 and 16, extending slightly beyond D-shaped member 3 at one end of the comb. The top baulk is positioned by the bolts 17 and nuts 18 above the short dents 9 and about one inch below the tops of the long dents 8, which are located in the apertures formed by the coils of the spring 19 and the two baulk members 15, 16. In inserting the spring 19 and members 15, 16, it is convenient to apply them just above the tips of the short dents 9, where the comb is more rigid by reason of the soldered points 13, and to slide the assembled top baulk up to its final position after the members 15 and 16 have been inserted in the spring 19. A metal cap 20 fits snugly over the tops of the dents and is detachably fixed to the handles by means of bolts 21 and wing-nuts 22. The cap protects the tops of the dents 9 and also helps to keep them in alignment.

Having described our invention, what we desire to secure by Letters Patent is:

1. A leasing comb comprising a bottom frame member; a series of long and short dents secured to said bottom frame member and alternating along the length thereof, the spaces for the accommodation of warp threads between each short dent and the two adjacent dents being of different depths, and a top frame member adapted to space apart and to secure in spaced relationship the tops of said long dents, said top frame member being detachable from the dents so as to leave the spaces between the dents clear for warp threads to be dropped between the dents.

2. A leasing comb comprising a bottom frame member; a series of long and short dents secured to said bottom frame member and alternating along the length thereof, the spaces for the accommodation of warp threads between each short dent and the two adjacent dents being of different depths, and a detachable top frame member consisting of a helical coil of wire the turns of which are adapted to be fitted between the long dents and two longitudinal members adapted to fit slidably inside said coil on each side of the series of long dents so as to lock said coil in position.

3. A leasing comb comprising a bottom frame member; a series of long and short dents secured to said bottom frame member and alternating along the length thereof, the spaces for the accommodation of warp threads between each short dent and the two adjacent dents being of different depths, rigid end frame members secured to each end of said bottom frame member and extending parallel to the dents, a detachable top frame member consisting of a helical coil of wire the turns of which are adapted to be fitted between the long dents and two longitudinal members adapted to slidably fit inside said coil on each side of the series of long dents so as to lock said coil in position, and means for

detachably securing the ends of said longitudinal members to said end frame members.

4. A leasing comb comprising a bottom frame member, a series of long and short dents secured to said bottom frame member and alternating along the length thereof, the spaces for the accommodation of warp threads between each short dent and the two adjacent dents being of different depths, rigid end frame members secured to each end of said bottom frame member and extending parallel to the dents, a detachable top frame member consisting of a helical coil of wire the turns of which are adapted to be fitted between the long dents and two longitudinal members adapted to slidably fit inside said coil on each side of the series of long dents so as to lock said coil in position, and means for detachably securing the ends of said longitudinal members to said end frame members in a position above said short dents but below the tips of said long dents so as to form a shallow comb projecting above said top frame member.

5. A leasing comb comprising a bottom frame member, a series of long and short dents secured to said bottom frame member and alternating along the length thereof, the spaces for the accommodation of warp threads between each short dent and the two adjacent dents being of different depths, rigid end frame members secured to each end of said bottom frame member and extending parallel to the dents, a top frame member consisting of a helical coil of wire the turns of which are adapted to fit between the long dents and two longitudinal members adapted to fit inside said coil on each side of the series of long dents so as to lock said coil in position, means for securing the ends of said longitudinal members to said end frame members in a position above said short dents but below the tips of said long dents so as to form a shallow comb projecting above said top frame member, a metal cap adapted to fit over the tips of said long dents with its lower edge clear of the upper edge of said top frame member, and means for securing the ends of said metal cap to said end frame members.
